US00D943575S

(12) **United States Design Patent** (10) Patent No.: **US D943,575 S**
(45) Date of Patent: **** Feb. 15, 2022**

(54) **HEADSET**

(71) Applicant: **Valve Corporation**, Bellevue, WA (US)

(72) Inventors: **Carl Samuel Conlee, IV**, Seattle, WA (US); **Ivan A. McCracken**, Bellevue, WA (US); **Jeremy Adam Selan**, Kirkland, WA (US); **Quentin Smith**, Seattle, WA (US); **Dustin Michael Horn**, Seattle, WA (US); **Clement Gallois**, Seattle, WA (US)

(73) Assignee: **Valve Corporation**, Bellevue, WA (US)

(**) Term: **15 Years**

(21) Appl. No.: **29/777,475**

(22) Filed: **Apr. 6, 2021**
